DRUM CLEANING MACHINE

Robert G. Cuillier, North Hollywood, Calif.
(931 N. Fairfax Ave., Los Angeles 46, Calif.)

Filed Mar. 10, 1959, Ser. No. 798,412

3 Claims (Cl. 134—107)

This invention relates generally to machines for cleaning garbage can drums and the like, and more particularly to such a machine in which the drum is spun about a vertical axis while both inner and outer surfaces are scoured and rinsed with many jets of hot cleaning liquid.

Restaurants, hotels, hospitals and similar large residential institutions have a very difficult problem of maintaining sanitary conditions in their kitchen areas because of the huge volume of garbage which must be temporarily stored near such an area prior to its removal. The tonnage of garbage delivered by a medium sized restaurant is so great that mechanical disposal means or incinerators are not satisfactory.

Moreover, the older food particles which accumulate on the surfaces of the garbage cans may be retained there for a period of time corresponding to several garbage collection periods, and by decaying, develop powerful odors in the immediate vicinity of the food preparation area.

When the garbage cans or containers have accumulated even small quantities of residual waste material, which remains after a garbage collection, their powerful odor attracts a swarm of flies even after the garbage has been collected, thus creating a severe danger of the spread of disease by the insects.

To combat these problems of unsanitary conditions, bad odor, and insect attraction, most modern restaurant facilities are compelled to clean the garbage containers, even after they have been emptied, by means of hoses, insecticide sprays, etc. In addition, there has been some relatively primitive advancement in the direction of servicing restaurant facilities by truck-carried tanks of spraying equipment.

The truck-carried or portable equipment is essential because it is not economically sound for most restaurant facilities to maintain large and cumbersome devices at the site of use at all times, not only because of economics, but also because of space and mechanical maintenance problems.

However, most truck transported and stationary garbage can cleaning means have left the major part of the hard work to manual labor. The operators must physically handle the filthy drums and work over both their internal and external surfaces with hose sprays.

Another disadvantage of the systems heretofore known, is that the filthy effluence of cleaning water and entrained garbage is usually discharged at the site, often into an overloaded sewer where the accumulating garbage particles eventually create a problem.

Another disadvantage of the waste of the discharge water is that powerful and valuable insecticides, soaps, and deodorizing materials are thereby lost after a single use, although they might be powerful enough to be suitable for several cleanings.

It is the major object of the present invention to overcome the foregoing and other problems by means of a portable garbage container cleaner, suitable for mounting on a truck body, which can clean the drums by motor driven means and without manual handling except for loading the drum before cleaning and removing it from the machine after cleaning.

It is another major object of the invention to provide

2

a garbage drum cleaning machine in which the cleaning liquid, including all soaps, insecticides, and deodorants, can be recycled to the mechanical cleaning means until its strength is entirely used and exhausted.

5 Another important object of the invention is to provide a mechanical garbage drum cleaning means which is sufficiently flexible in structure to receive drums which vary slightly in size because of variation in manufacture or because of damage experienced during the rough 10 handling to which such containers are frequently subjected.

The foregoing and other objects and advantages of the invention will best be understood from the following detailed description of one specific embodiment of 15 the invention, taken in connection with the accompanying drawings, in which:

Figure 1 is a plan sectional view of the described embodiment of the invention, the plane of the section being taken approximately at the plane indicated by the numerals 1—1 in Figure 2; and

20 Figure 2 is a vertical sectional view as viewed at a plane through the lines indicated by the numerals 2—2 in Figure 1.

In Figure 1, the drum cleaning machine, indicated generally by the arrow 10 is seen to be comprised principally of a cylindrical drum cleaning tank 11 which is nested into a cleaning liquid reservoir 12.

A portable gasoline engine 13 is fitted in closely at the right side of the tank 11 and drives a pump 14 and a 30 sprocket 15 mounted on a power shaft 16 to operate other parts of the machine 10, as will be described in detail hereinafter.

The operator may conveniently stand beside both the cleaning tank 11 and the engine 13 and reach the control handle 17 by means of which he may operate a clutch 18 for connecting or disconnecting the power shaft 16 to the engine 13.

As seen in Figure 2, the cleaning tank 11 is supported at a somewhat higher elevation than the liquid reservoir 12 by means of a framework of angle iron 20, and the bottom region of the container 11 is in open communication with the interior of the reservoir 12 through a liquid return opening 21.

The reservoir 12 contains a cleaning liquid as indicated at 22 which is preferably a water solution of a strong liquid soap or detergent, some powerful insecticide such as DDT or chlorodane, a commercial deodorant, and a small amount of pine oil or the like to impart a pleasant odor to the cleaned garbage drums.

50 The upper surface of the liquid 22 must not be so high as to impede the spraying operation which takes place inside the cleaning tank 11, and which will be described hereinafter.

The liquid 22 may be drained away by means of the 55 drain valve 23 when the efficacy of the liquid is exhausted.

Preferably, the truck carries a butane fuel tank which is connected to gas burner supply line 24 and supplies burners 25 and 26, seen in dashed outline in Figure 1, 60 and in end view in Figure 2, which burners, when lighted, are sufficient to raise the liquid 22 to or very near the boiling point.

The pump 14 withdraws cleaning liquid from the reservoir 12 by way of an intake line 30, and delivers it 65 under pressure of 60 or more pounds per square inch to a pressure discharge line 31, for delivery to the various spray lines to be described hereinafter.

The intake line 30 is provided with a strainer 32 at the intake in the reservoir 12, but inevitably, many hard 70 chunks of garbage particles pass through the pump. Not only must the pump 14 be of a type which can withstand the passage of some solid materials, but the discharge

line 31 and parts of the apparatus downstream from it must be protected against the possibility of clogging and development of over pressure in the discharge line 31. Consequently, a bypass line 33 is provided for returning the cleaning liquid directly from the pump discharge to the reservoir 12, by way of a safety valve 34, whenever the pressure in discharge line 14 exceeds a predetermined safe value.

The extremely efficient cleaning achieved by the invention is accomplished by spinning the garbage drum in an inverted position within the drum cleaning tank 11, as indicated in Figure 2, while scouring and rinsing both its internal and external surfaces with powerful jets of hot and steaming cleaning liquid.

A heavy bearing 40 is welded to the underside of the bottom of the tank 11, and a short, vertically disposed hollow shaft 41 is rotatably mounted therein. It is important to provide good liquid seals 42 and 43 to prevent unwanted leakage of liquid from within the cleaning tank 11 to the work floor 44, where it would wet the feet of the operator and make the work floor dangerously slippery.

The hollow shaft 41 has a suitable upper shoulder 45 to hold it in position, and has a bevel gear 46 keyed and fastened to its lower and external end.

A small bevel pinion 47 is rotatably supported in a bracket 48 on the bottom of the tank 11, and rotates with a small sprocket 49 which is driven through a chain 50 (see Figure 1) by sprocket 15 on power shaft 16, as already described.

On the upper portion thereof, the hollow shaft 41, inside the lower part of the drum cleaning tank 11, carries at its upper end a set of resilient gripping means, indicated generally by the numeral 51, for firmly holding the inverted garbage drum, indicated by the phantom lines 52, during spinning, and spaced a short distance below that a drum supporting spinning table 53. Preferably, the spinning table 53 is a disc of steel welded to the hollow shaft 41 at its center, and provided with drain openings 54.

The resilient drum retaining means 51 is comprised of a central disc 55, spoke rods 56 extending from disc 55, cylindrical leaf spring means carried on the outer ends of the spokes 56, and upwardly extending spring fingers 58.

The plan view of Figure 1 illustrates that reinforcing cord rods 59 may also be used, if desired, but these cord bars are omitted from the illustration of Figure 2 for purposes of clarity.

It will be seen that the resilient construction of the retaining means 51 will grip the interior surface of garbage drums which vary substantially in size from the preferred standard. Indeed, a smaller drum may be cleaned on the device by simply inverting it onto the cord supporting bars 59 and retaining it thereon by means of the engagement between the resilient spring fingers 58 and its external surface.

The hot liquid is delivered in sprays to the surfaces of the drum 52 by way of an internal axial spray line 61 and an external spray line 62. An internal scouring spray line 63 is also provided for purposes to be described hereinafter. The hot liquid under pressure flows from the pressure line 31 to the valve 64 (see Figure 1), and is delivered from that point to two horizontal pipes 65 and 66.

Supply pipe 65 is connected to an elbow 67 which discharges upwardly through the vertically disposed axial spray line 61, which is supported at elbow 67 so as to stand free and stationary within the hollow shaft 41.

At its upper and lower end, the axial spray line is provided with radial lines 68 and 69 which deliver liquid to the scouring line 63. Preferably, the line 61 is broken by a plumber's coupling 70 to make easy assembly and disassembly.

A row of fine orifice holes 71 extends vertically the entire length of axial line 61, and projects a heavy spray

75 of rinsing liquid against the interior surface of the drum 52. The upper radial line 68, and its associated elbows 72 and 73 are also pierced with holes to provide spray cleaning for the inverted interior bottom of the garbage drum 52.

A vertical row of fine orifice holes 74 is provided along the outer surface of the scouring line 63. It will be seen that the scouring line 63 is much closer to the internal surface of the drum 52 than is the axial rinsing line 61; and is thus able to deliver a more violent scouring spray. This scouring action may be accentuated, if desired, by making the holes 74 somewhat smaller in diameter than the holes 71. The scouring line 63 and the axial line 61 thus coact to subject the interior cylindrical surface of the drum 52 to an alternate sharp scouring jet and a heavy flooding and rinsing jet.

Preferably, a shielding baffle 75 encircles the lower end of the axial line 61 to prevent excessive flow of water from being directed downwardly into the hollow shaft 41 through the opening in the center of the disc 55.

The external cylindrical surface of the drum 52 is cleaned by water delivered through line 66 to one or more vertical external spray lines 62. As seen in Figure 2, vertical spray line 62 is provided with a vertical row of orifice openings 76 which spray the entire vertical length of the external surface of the drum 52.

Valve 64 is a three-way selector valve by which the operator can direct liquid to both inner and outer sprays, or all to either line 65 or 66.

30 It will be understood, that more than one vertical row of spray holes 71, 74 and 76 may be provided, and that these spray holes do not necessarily have to be in a perfect vertical row.

35 When the operator throws the machine into operation by throwing operating lever 17, the pump 14 simultaneously begins to deliver the heavy scouring and rinsing sprays to the interior and exterior surfaces of the drum 52, as indicated generally by the spray jets 77, and at the same time, sprocket 15 and the mechanism connected therewith, rapidly rotates the spinning table 53 and the drum 52, mounted thereon.

30 The violent spraying and spinning action of the machine 10 would naturally tend to throw water out of the upper opening of the tank 11, and it is therefore necessary to provide a tightly fitting cover 80 which is hinged to the drum cleaning tank 11 by hinge 81, and is fastened down when closed by hinged latch 82. Preferably, a cover support 83 is provided so that the cover may be supported in an open position.

50 The external upper edge of the drum 11 should be surrounded with a sealing means comprised of a ring channel 84 containing a neoprene O-ring or other gasket means 85 to seal the interior of the cleaning tank 11.

55 It will be noted that by nesting the tank 11 into the reservoir 12, as illustrated in the preferred specific embodiment of the invention, great structural strength is achieved and the entire system is reinforced against vibration produced by spinning.

60 Moreover, the nesting construction makes it possible to return the cleaning liquid, together with all the entrained garbage particles directly through the large opening 21 to the reservoir 12, thus eliminating any possibility of clogging a return line with large particles.

65 However, it is not to be understood that my invention is confined to the details of the specific embodiment illustrated in the drawings and described in detail herein. It will be obvious to those skilled in the art of constructing similar machines that many simplifications, or elaborations, or alterations for different purposes, may be made in the device without departing from the spirit and scope of the invention as described and defined in the appended claims.

I claim:

1. A drum cleaning machine which includes a drum

cleaning tank having an opening at the top; a vertically disposed hollow shaft rotatably mounted in the bottom of said tank; a spinning table mounted on the upper end of said hollow shaft and rotatable therewith, and having a central opening communicating with the interior of said shaft; resilient cylindrical leaf spring members extending horizontally from said spinning table near the perimeter thereof; vertical spring members extending upwardly from the unsupported ends of said cylindrical leaf spring members; motor means for driving said hollow shaft to rotate said table; a pump means including strainer intake means and a high pressure discharge line; an axial spray line connected to said high pressure discharge line and extending vertically upward through said hollow shaft and the opening in said spinning table to the upper part of said drum cleaning tank, said axial spray line having spray orifice openings extending from its lower to its upper end for delivering cleaning liquid from said pressure discharge line to the interior surfaces of a drum inverted and mounted on said spinning table; a scouring spray line vertically disposed above said spinning table and supported by and connected to said axial spray line, but at a line much closer to the location of the internal surface of a drum carried on said spinning table than said axial spray line, said scouring spray line being provided with orifice openings throughout its length, said orifice openings being smaller than the openings in said axial spray line and adapted to project a scouring jet on the internal surface of a drum mounted on said spinning table; an external spray line vertically disposed in said drum cleaning tank at a radius external to the radius of said spinning table and of a drum mounted thereon, and connected to said pressure discharge line, said external spray line having discharge openings along its entire length from the locality of the spinning table to the upper end of said tank, said openings being oriented toward the location of the external surface of a drum mounted on said spinning table; and heated reservoir means connected of deliver cleaning fluid to said pump intake and receiving return flow from the lower end of said tank.

2. A drum cleaning machine which includes: a drum cleaning tank having an opening at the top; a vertically disposed hollow shaft rotatably mounted in the bottom of said tank; a spinning table mounted on the upper end of said hollow shaft and rotatable therewith, and having a central opening communicating with the interior of said shaft; resilient cylindrical leaf spring members extending horizontally from said spinning table near the perimeter thereof; vertical spring members extending upwardly from the unsupported ends of said cylindrical leaf spring members; bevel gear means at the lower end of said hollow shaft for rotatably driving said shaft; motor means including a power shaft; sprocket and chain means on said power shaft for driving said hollow shaft through said hollow shaft gear means; a pump means driven by said power shaft, said power means including strainer intake means and a high pressure discharge line; an axial spray line connected to said high pressure discharge line and extending vertically upward through said hollow shaft and the opening in said spinning table to the upper part of said drum cleaning tank, said axial spray line having spray orifice openings extending from its lower to its upper end for delivering cleaning liquid from said pressure discharge line to the interior surfaces of a drum inverted and mounted on said spinning table; a scouring spray line vertically disposed above said spinning table and supported by and connected to said axial spray line, but at a line much closer to the location of the internal surface of a drum carried on said spinning table than said axial spray line, said scouring spray line being provided with orifice openings throughout its length, said orifice openings being smaller than the openings in said axial spray line and adapted to project a scouring jet on the internal surface of a drum mounted on said spinning table; an external spray line vertically disposed in said drum cleaning tank at a radius external to the radius of said spinning table and of a drum mounted thereon, and connected to said pressure discharge line, said external spray line having discharge openings along its entire length from the locality of the spinning table to the upper end of said tank, said openings being oriented toward the location of the external surface of a drum mounted on said spinning table; and heated reservoir means connected of deliver cleaning fluid to said pump intake and receiving return flow from the lower end of said tank.

scouring jet on the internal surface of a drum mounted on said spinning table; an external spray line vertically disposed in said drum cleaning tank at a radius external to the radius of said spinning table and of a drum mounted thereon, and connected to said pressure discharge line, said external spray line having discharge openings along its entire length from the locality of the spinning table to the upper end of said tank, said openings being oriented toward the location of the external surface of a drum mounted on said spinning table; heated reservoir means mounted on the external surface of said drum cleaning tank, at an elevation downwardly displaced from said tank, and having open communication with the lower end of said tank, and communicating with said pump means through said strainer intake means.

3. A drum cleaning machine which includes: a drum cleaning tank having an opening at the top; a vertically disposed hollow shaft rotatably mounted in the bottom of said tank; a spinning table mounted on the upper end of said hollow shaft and rotatable therewith, and having a central opening communicating with the interior of said shaft; resilient cylindrical leaf spring members extending horizontally from said spinning table near the perimeter thereof; vertical spring members extending upwardly from the unsupported ends of said cylindrical leaf spring members; bevel gear means at the lower end of said hollow shaft for rotatably driving said shaft; motor means including a power shaft; sprocket and chain means on said power shaft for driving said hollow shaft through said hollow shaft gear means; a pump means driven by said power shaft, said power means including strainer intake means and a high pressure discharge line; an axial spray line connected to said high pressure discharge line and extending vertically upward through said hollow shaft and the opening in said spinning table to the upper part of said drum cleaning tank, said spray line having spray orifice openings extending from its lower to its upper end for delivering cleaning liquid from said pressure discharge line to the interior surfaces of a drum inverted and mounted on said spinning table; a scouring spray line vertically disposed above said spinning table and supported by and connected to said axial spray line, but at a line much closer to the location of the internal surface of a drum carried on said spinning table than said axial spray line, said scouring spray line being provided with orifice openings throughout its length, said orifice openings being smaller than the openings in said axial spray line and adapted to project a scouring jet on the internal surface of a drum mounted on said spinning table; an external spray line vertically disposed in said drum cleaning tank at a radius external to the radius of said spinning table and of a drum mounted thereon, and connected to said pressure discharge line, said external spray line having discharge openings along its entire length from the locality of the spinning table to the upper end of said tank, said openings being oriented toward the location of the external surface of a drum mounted on said spinning table; heated reservoir means mounted on the external surface of said drum cleaning tank, at an elevation downwardly displaced from said tank, and having open communication with the lower end of said tank, and communicating with said pump means through said strainer intake means; and safety valve means connecting said pressure discharge line from said pump with said heated reservoir means and adapted to recycle liquid directly from said pump discharge to said reservoir whenever said discharge pressure exceeds a predetermined value.
